UNITED STATES PATENT OFFICE.

FRANK X. VERANICH, OF WEST ALLIS, WISCONSIN, ASSIGNOR OF ONE-HALF TO
FRANK BRANDSTÄTTER, OF WEST ALLIS, WISCONSIN.

FIRE-ALARM SYSTEM.

1,160,795.

Specification of Letters Patent. Patented Nov. 16, 1915.

Application filed January 12, 1915. Serial No. 1,818.

To all whom it may concern:

Be it known that I, FRANK X. VERANICH, a subject of the Emperor of Austria-Hungary, residing at West Allis, in the county of 5 Milwaukee and State of Wisconsin, have invented new and useful Improvements in Fire-Alarm Systems, of which the following is a specification.

This invention relates to a thermostatic-10 electric fire alarm system, and its object is to provide an alarm system which is simple of construction, reliable and efficient in operation, adapted for residences, factories and other buildings, capable of use in conjunction with an outside fire alarm or telephone system, and susceptible of regulation and control to vary the action of the apparatus to give the alarm at any predetermined temperature or temperatures, as occasion 15 may require, as well as to indicate the source of the fire.

The invention consists of the features of construction, combination and arrangement 20 of parts hereinafter fully described and claimed, reference being had to the accompanying drawings in which:—

Figure 1 is a diagrammatic sectional elevation of a fire alarm system embodying my invention. Fig. 2 is a view of the alarm 25 device showing the positions of the parts during the alarm action. Fig. 3 is a detail view of the gears of the bell ringing mechanism. Fig. 4 is a detail view of the ringing mechanism actuated by said gears. Fig. 5 is a perspective view of the alarm device 30 as it appears externally. Fig. 6 is a detail section on line 6—6 of Fig. 1 showing the adjustable binding post of the thermostat.

The apparatus includes a thermostatic 35 circuit controlling device A and an alarm device B controlled therefrom, any number of which thermostats and alarm devices may be included in a system, installed in a residence, factory or other building. The thermostat A preferably is of the form shown, consisting of a glass or other bulb 1 containing a mercury column 2 and provided with temperature graduations, in line with 40 which are arranged contacts 3, preferably of platinum wire, which project into the path of the mercury column. These contact wires 3 connected with metallic conducting plates 4 which are insulated from each other, as shown at 5. The plates form part of a 45 suitable frame work including spaced guide

bars 5 and 6, the latter having a series of rack teeth 7. Adjustably mounted upon the bars 5 and 6 is a binding post 8, upon which is pivotally mounted a locking dog 9 having teeth 10 to engage the rack teeth 7 of the 50 bar 6, so that the binding post may be locked at any elevation in line with any of the contact plates 4. The dog 9 has a finger piece 11 by which it may be manipulated and springs 12 for maintaining it in lock 55 engaging position, and it is also provided with a contact finger 13 which is adapted to engage the socket in any of the contact plates 4, whereby the thermostat may be set to operate the alarm at any desired temperature. A second binding post 14 connects with a contact wire 15 disposed at the lowest 60 temperature point at which the thermostat is adapted to operate, and connected with the respective binding posts 8 and 14 65 are conductors 15 and 16 which form part of an alarm starting or releasing circuit, as 70 hereinafter described.

The alarm mechanism B comprises a suitable casing 17 within which is inclosed an 75 electromagnet 18 controlling a spring retracted armature 19, and with one of the coils of said magnet the wire 16 is connected. The armature 19 is connected with a pivoted dog or detent 20 having a tooth 80 85 21 to engage the teeth of a ratchet wheel 22 driven in operation by a coiled spring 23, designed to be manually wound in any preferred manner. The wheel 22 carries pins or projections to engage and operate a pivot 90 trip member 24 which controls a combined 95 detent and switch lever 25, the upper end of which is movable under the pressure of said detent into engagement with a stop pin 26. The lower arm of the lever 25 carries a locking or stop tooth 27 adapted for engagement with the teeth of a ratchet wheel 28, said arm being arranged to control a spring pressed switch 29 connected 100 with a contact 30 and movable into and out of engagement with a contact 31 which is connected with the other coil of the electromagnet 18 by a conductor 32, whereby in the operation of the device a starting circuit is provided in which the thermostat and electromagnet are arranged and which circuit is closed by the thermostat to throw the starting wheel 22 into action and then broken by movement of the switch 29 out of engagement with the contact 31, so as 105 110

to break the starting circuit and throw the starting mechanism out of action. In this operation it will be understood that the wheel 22 will be relocked against movement 5 by the retraction of the armature 19 upon the deenergization of the electro-magnet, but that the detent 24 will remain retracted and will hold the combined detent and switch operating member 25 also retracted to permit the wheel 28 to turn for the actuation 10 of the alarm mechanism.

The wheel 28 is adapted to be driven by means of a coil spring 33 and is adapted to operate a transmission gear 34, loosely 15 mounted upon the same shaft or arbor as the ratchet wheel 28, the spring 33 being designed to be manually rewound whenever run down. A spring pressed clutch or check pawl 35 pivoted to the wheel 34 engages 20 the teeth of the ratchet wheel 28 and is adapted to permit said ratchet wheel to have independent motion during the rewinding action of the spring, while it couples the wheel and gear together for 25 conjoint motion during the unwinding of the spring and operation of the alarm mechanism.

The gear 34 meshes with a pinion 36 which is fixed to revolve with a pair of toothed 30 disks or wheels 37 and 38. The wheel 38 is provided around its periphery with ratchet teeth except at one point, where the teeth are omitted, which ratchet teeth engage a finger 39 projecting from a pivoted vibrating 35 lever 40 arranged to actuate an oscillating bell hammer or clapper 41 which projects externally of the casing 17 for coöperation with a bell 42 supported upon the exterior of said casing. On each revolution 40 the wheel operates the clapper a predetermined number of times, with an interval of rest, thereby indicated by the number of strokes of the bell that a fire has broken out in some portion of the building, the location 45 of which is designated by the given number of strokes or taps.

The wheel or disk 37 is of the mutilated type and provided with spaced sets or series of teeth 43 and 44, and also with a set of 50 teeth or projections 45 disposed at one side of said disk and on a line between adjacent end teeth of the sets 43 and 44. The teeth 43 are adapted to transmit motion to a pivoted, vibrating circuit make-and-break lever 55 46 operable at spaced intervals and predetermined numbers of times by the teeth 43 and 44 to control the alarm circuit for transmitting a signal to a town or city fire alarm system or to a telephone exchange, indicating 60 that a fire has broken out at the protected point, a designated number of which is given by the number of times the circuit is made and broken at predetermined periods by the actuation of the member 46. 65 A switch resetting lever 47 is disposed op-

posite the lever 46 and is designed to be operated by the tappets or projections 45 at intervals during the cessation of operation of the lever 46 to insure the retraction of the switch and obviate all liability of its becoming struck or fused permanently in a circuit closing position. 70

The setting levers 46 and 47 control an intervening spring retracted switch actuating member 48 movable to adjust the spring controlled switch member 49 into and out of engagement with a contact or circuit terminal 50, the said switch being normally in engagement with another contact or circuit terminal 51. The said contacts or terminals 50 and 51 are respectively connected by conductors 52 and 53 with terminals 54 and 55 which connect with main line wires 56 and 57 from a suitable source of current supply, as a battery or alarm circuit system, 80 telephone system or ordinary electric service system, it being understood that the alarm devices which are controlled by the actuation of the switch 49 may be either within or without the protected structure. As 85 shown, the local starting circuit in which the electromagnet 18 is arranged is completed by the connection of the conductor 15 with the terminal 54, and also by the connection of a conductor 58 connecting the contacts 30 and 54. 90

In practice, it will be understood that the thermostats may be arranged at desired points throughout a building and set to affect the sounding of an alarm at any desired temperature, and that the alarm devices, any number of which may be used, may also be placed at desired points within the building, and such alarm or devices connected with an outside alarm circuit when desired. 100 It will also be evident that when a fire starts in any portion of the protected building, the starting mechanism will be thrown into operation to release the alarm mechanism for actuation, which will thereupon not only operate the local alarm signal, but will also operate an outside alarm, giving the exact 105 point of location of the fire. 110

I claim:—

1. In a thermostatic electric fire alarm system, the combination with a thermostatically controlled starting mechanism, of a spring actuated motor controlled thereby, a gear driven by said motor, a disk driven by said gear and having spaced series of peripheral teeth and a series of lateral teeth, an alarm circuit, a switch controlling the same, and switch closing and opening levers controlled respectively by the peripheral and lateral teeth of said disk. 115

2. In a thermostatic electric fire alarm system, the combination with a thermostatically controlled starting mechanism, of a spring actuated motor controlled thereby, a gear driven by said motor, a disk driven by said 120 125

5 gear and having spaced series of peripheral teeth and a series of lateral teeth, an alarm circuit, a switch controlling the same, switch closing and opening levers controlled respectively by the peripheral and lateral teeth of said disk, a second disk driven by said gears and forming a mutilated gear, and an alarm device actuated with intervals of rest by the teeth of said gear.

10 3. In a thermostatic electric fire alarm system, the combination of a spring actuated motor, a spring actuated starting device, a detent for holding the motor from operation, means controlled by the starting device for
15 releasing said detent, a gear driven by the motor, a disk driven by said gear and hav-

ing spaced series of peripheral teeth and a series of lateral teeth, an alarm circuit, a switch controlling the same, switch closing and opening levers controlled respectively 20 by the peripheral and lateral teeth of said disk, a second disk driven by said gears and forming a mutilated gear, and an alarm device actuated with intervals of rest by the teeth of said mutilated gear.

25

In testimony whereof I affix my signature in presence of two witnesses.

FRANK X. VERANICH.
